UNITED STATES PATENT OFFICE.

CHARLES W. MEADOWCROFT, SR., OF PHILADELPHIA, PENNSYLVANIA.

RIVETING-MACHINE.

1,034,480.

Specification of Letters Patent.

Patented Aug. 6, 1912.

Application filed January 22, 1912. Serial No. 672,548.

To all whom it may concern:

Be it known that I, CHARLES W. MEADOWCROFT, Sr., a citizen of the United States, residing at Philadelphia, in the county of 5 Philadelphia and State of Pennsylvania, have invented certain new and useful Improvements in Riveting-Machines, of which the following is a specification.

My invention relates to improvements in 10 riveting machines, the object of the invention being to provide a rotary element carrying a circular series of balls adapted to impart a rapid succession of blows to a hammer, and preferably through the medium of a ball interposed between the hammer and the balls of the rotary element.

A further object is to provide a continuously revolving rotary element containing a circular series of pockets in which balls are 20 loosely mounted, and project beyond the periphery of the rotary element, said balls adapted to engage a ball supported in a pivoted arm and located against the upper end of a hammer, when said last-mentioned ball and arm are elevated by the 25 action of suitable mechanism pressing a rivet against the lower end of the hammer, and provide mechanism for imparting a rotary motion to the hammer simultaneously with its reciprocating movement 30 imparted by the balls.

A further object is to provide an improved rivet carrying disk or table and mechanism controlling the movement of the 35 table, whereby the table is revolved and momentarily stopped and locked in a position to present a rivet between the hammer above referred to and a vertically movable anvil, the movement of the latter being automatically 40 controlled and timed in accordance with the movement of the table.

A further object is to provide improved 45 means for elevating the anvil, and improved means for engaging and holding the rivet in position to receive the blows of the hammer, said holding means comprising a spring-pressed sleeve located within a nose adjustably fixed in the structure, and with relation to which the hammer is adjustable to compensate for wear.

With these and other objects in view, the invention consists in certain novel features of construction and combinations and arrangements of parts, as will be more fully

hereinafter described and pointed out in the 55 claims.

In the accompanying drawings: Figure 1, is a view in side elevation illustrating my improvements. Fig. 2, is a view in vertical longitudinal section through the center of 60 the hammer operating structure. Fig. 3, is a view in section on the line 3—3 of Fig. 2. Fig. 4, is a view in front elevation illustrating the rivet carrying disk or table and its operating mechanism. Fig. 5, is a view in 65 section on the line 5—5 of Fig. 2. Fig. 6, is a view in section on the line 6—6 of Fig. 2. Fig. 7, is a detail sectional plan view illustrating the mechanical movement which controls the operation of the disk or table, and 70 Fig. 8, is a detail view illustrating the modification.

1, represents a support to which a bar 2 is secured by bolts 3, and nuts 4, and on this bar 2, a bracket 5 is secured by bolts 6. To 75 the upper end of this bracket 5, the casing 7 of my improved hammer operating mechanism is secured by screws 8, and this casing illustrated more clearly in Figs. 2 and 3, is of general cylindrical form throughout its 80 upper portion, and somewhat rectangular at its lower portion, having a removable plate 9 at one side secured in place by screws 10.

The casing head 11 which is located parallel with the plate 9, is provided with a 85 central opening 12 alining with a central opening 13 in plate 9, and in these openings 12 and 13, bearings 14 and 15 respectively are secured by means of screws 16, which extend through the head and plate respectively, and are screwed into annular flanges 17 on the inner ends of the bearings.

A shaft 18 is mounted to turn in the bearings 14 and 15, and is provided with an annular enlargement 19 located in a circular 95 recess in the bearing 14, and limiting the movement of the shaft in this direction. On the shaft 18, within the casing, my improved rotary element 20 is secured. This rotary element comprises two circular relatively thick disks secured together by rivets 100 21. Both of these disks have central openings one of which is screw-threaded to engage screw-threads 22 on shaft 18, and securely lock the rotary element to the shaft, 105 and compel it to revolve therewith. This rotary element is made with an annular groove 23 into which a circular series of

balls 24 project. These balls are mounted in circular sockets 25 in the rotary element, and such sockets are formed by recessing the two members as clearly shown. The circular recesses 25 are greater than half of a circle, so that the outward movement of the balls are limited, yet the balls are loosely mounted to allow them free rotary motion as well as inward and outward motion as 5 will more fully hereinafter appear. These 10 balls, as the rotary element is revolved, are adapted to engage a ball 26 in a pivoted arm 27, when the said ball is elevated above its normal position. The ball 26 rests upon 15 the upper end of a hammer 28, and is loosely confined within a recess in the arm 27. Arm 27 is also composed of two members secured together by rivets 29, and said arm at one end, is made with laterally projecting 20 trunnions 30 projecting through bearings 31 in head 11 and plate 9.

An oil cup 32 is preferably provided on the upper end of the casing, and has a wick 33 projecting into the casing and adapted 25 to be engaged by the balls 24, and to lubricate all of the parts of the hammer operating mechanism.

The lower end of the casing 7 is made with an opening 34, which opening is normally 30 closed by a plate 35. This plate 35 is secured to the casing by means of a screw 36, the latter operating as a hinge pin to allow the plate to be swung to one side whenever desired. This plate 35 is locked 35 in closed position by a thumb screw 37, and is provided with a circular barrel 39 through which the hammer 28 projects.

In the circular barrel 39, a gear wheel 40 is located, and is in mesh with an idler 41 supported upon a journal 42 riveted into 46 plate 35, and held in place by means of a nut 43 and washer 44. One side of the barrel is cut out to permit the gear 40 to mesh with the idler 41, and the latter normally 45 meshes with a pinion 45 fixed to a shaft 46 supported in bearings 47 on the head 11. This shaft 46 is connected by miter gears 48 with shaft 18, and the latter is driven by a pulley 49 connected with any suitable source 50 of power (not shown).

The hammer 28 above referred to is rectangular in form, and projects through an opening of similar shape in gear 40, so that while the hammer is permitted to reciprocate in the gear, the gear and the hammer 55 are keyed to turn together.

A spacing washer 50 is located in the barrel 39, and holds the gear in the lower portion of the barrel, and said gear has a circular 60 extension 51 which operates as a journal to center the gear and maintain it in proper relation to the other parts of the mechanism.

The barrel 39 is made with a depending 65 lug 52, which projects into a recess 53 in a

collar 54, and holds the collar against any possibility of rotary movement. This collar 54 and the lower restricted end of the barrel 39 are screw-threaded for the reception of a nose piece 55, and the latter is securely clamped after adjustment by means of a screw 56, located in the split end of the collar, as clearly shown in Fig. 6. This nose is of two internal diameters separated by an annular internal flange 57. The hammer 75 28, while angular throughout its upper portion, is cylindrical throughout its lower portion, and hence at the juncture of the angular and cylindrical portions, a shoulder is formed which normally bears upon a series 80 of washers 58, which may be removed one at a time as the hammer wears. In the lower smaller internal diameter of the nose, a sleeve 59 is positioned around the hammer, and is pressed downwardly by means 85 of a coiled spring 60, and a set screw 61 projects through a slot in the nose, and against said sleeve 59 to limit the movement of the sleeve. This sleeve operates to hold the rivet when the hammer is pressed upwardly, 90 and prevent any displacement of the rivet during the initial operation.

To the bar 2, at one end, parallel plates 61 are secured by bolts 62, and support at their outer ends, a transversely positioned 95 shaft 63. On this shaft 63, a gear wheel 64 is secured, and meshes with a pinion 65 on a stub 66 secured in one of the side plates 61. On this stub 66, a relatively large pulley 67 is secured, and is connected by a 100 strap 68 with a relatively small pulley 69 on shaft 18, so that motion is transmitted to shaft 66 at a very reduced speed over the motion of shaft 18. The plates 61, at top and bottom, are provided with perforated 105 ears 70 to which transverse bars 71 are secured by screws 72. These transverse bars have bearings 73 for a vertical shaft 74 on the upper end of which a rivet carrying disk or table 75 is mounted. The shaft 63 110 has fixed thereon, a sleeve 76, and on this sleeve an integral segmental worm 77 and a segmental annular key 78 are provided. A bar 102 is secured to shaft 74, and has upwardly projecting pins 103 which project 115 through openings in plate 75, and compel the plate to turn with the shaft, yet allow it vertical movement. This segmental worm and key engage between the teeth of a worm wheel 79, fixed to shaft 74. The teeth of this worm wheel 79 are alternately beveled and straight, the beveled teeth engaged by the segmental worm 77, and the straight teeth by the key 78. More correctly speaking, the teeth are so shaped that they are beveled at 125 one side, and straight at their other side, so that the recesses between the teeth are alternately inclined and straight, the segmental cam engaging in the beveled recesses, 130 serves to move the wheel 79, and shaft 74

a distance equal to the length of two teeth, and as the segmental worm rides out from between the teeth, the key 78 enters the straight recess and locks the shaft against 5 possibility of movement. By this mechanism, an intermittent rotary feed is transmitted to the shaft 74, and disk or table 75, and the length of this movement is just such as to move the table so as to present one 10 rivet after another in position below the hammer, and momentarily hold the table in this position by reason of the movement of the key between the teeth of the worm wheel.

On shaft 63, cams 80 are secured and engage rollers 81 in the bifurcated ends of levers 82. These levers are fulcrumed between their ends on a transverse shaft 83 mounted in the plates 61, and at their opposite ends are connected by a transverse 20 bar 84, and engage under a bracket 85. The bracket 85, at its upper portion, has a clamping plate 86 which secures it around a hollow spindle 87. In this hollow spindle 87, an anvil 88 is mounted, and its downward 25 movement is limited by a fixed screw 89 in a bracket 90 secured to the plates 61. The bracket 85 is also provided with parallel threaded rods 91, on which an arm 92 is held by nuts 93, and engages under the 30 lower end of the spindle 87, thereby relieving the clamping plate 86 of the entire duty of connecting the bracket and the spindle.

A bar 94 is secured to the levers 82 by 35 means of bolts 95, and this bar is provided with an opening 96 in its free end for the attachment of any suitable manually operating means (not shown), so that the mechanism may be operated manually as 40 well as automatically.

An oil cup 97 is preferably provided to lubricate shaft 18, and is secured to the bearing 15.

Instead of employing the ball 26 as illustrated in Fig. 2, I might employ a block 98 which is fixed against vertical movement in an arm 99 by means of a rivet 100. The upper end of this block 98 is beveled as 50 shown at 101, and this beveled end is adapted to be engaged by the balls 24, while the lower end of the block engages the hammer 28.

In operation, the rivet, and if desired the work, is supported on the table or disk 75, and as this disk or table is moved step by step through the action of the segmental worm 77, key 78, and worm wheel 79 to present the rivet in position between the anvil 88 and the hammer 28, cams 80 operate to move levers 82 and elevate the spindle 87 and anvil 88. This movement exerts an upward pressure on the hammer, the rivet being steadied by means of the spring-pressed sleeve 59. As the hammer is moved 65 upwardly, it causes the arm 27 to pivot, and

the ball 26 to move into the path of balls 24. The rapid centrifugal action of the rotary element 20 causes these balls 24 to impart blows to ball 26, and the force of these blows are regulated by the upward pressure 70 on the hammer as will be readily understood. The rotary element is revolving rapidly, and while the key 78 holds the table securely locked against movement, for but a relatively short period, during such period 75 a great number of blows are struck by the balls, and the rivet is completely upset. This timing of the stop, and the number of blows struck can be controlled absolutely by the speed of the mechanism, and the desired 80 results obtained.

By providing balls, they continually present new surfaces for contact. In other words, the engagement of balls 24 with ball 26 causes the balls to revolve and they do not 85 wear at any one point, but the wear is evenly distributed throughout the circumference. When any of the balls wear, they can be readily replaced, and they are of course made of the hardest possible steel to 90 withstand the necessary wear to which they are subjected. The parts are so constructed and assembled that access may be readily had to the interior of the casing for purposes of examination and repair, and the device 95 may be kept perfectly clean and lubricated so as to produce the best possible results.

Various slight changes might be made in the general form and arrangement of parts 100 described without departing from my invention and hence I do not limit myself to the precise details set forth, but consider myself at liberty to make such changes and alterations as fairly fall within the spirit 105 and scope of the appended claims.

Having thus described my invention, what I claim as new and desire to secure by Letters Patent is:

1. A riveting machine, comprising a hammer, a circular rotary element having an annular series of curved recesses therein, and balls located within the recesses and adapted to impart movement to the hammer, substantially as described. 110

2. A riveting machine, comprising a hammer, a circular rotary element having an annular series of curved recesses therein, balls located within the recesses and adapted to impart movement to the hammer, said 120 rotary element having an annular groove in its periphery into which the balls project, substantially as described.

3. A riveting machine, comprising a hammer, a circular rotary element having an 125 annular series of curved recesses therein, balls located within the recesses and adapted to impart movement to the hammer, said rotary element having an annular groove in its periphery into which the balls project, 130

and said first-mentioned recesses at their outer ends smaller than the diameter of the ball, whereby the outward movement of the balls is limited, substantially as described.

5. A riveting machine, comprising a hammer, a circular rotary element having an annular series of curved recesses therein, and balls located within the recesses and adapted to impart movement to the hammer, said element comprising two disks secured together and having ball receiving recesses in their opposed faces, substantially as described.

5. A riveting machine, comprising a casing, a rotary element mounted in the casing, a circular series of balls supported in the rotary element, a hammer projecting into the casing, an arm pivotally supported in the casing, a device supported by said arm, and adapted to be moved by the hammer into the path of movement of the balls, substantially as described.

6. A riveting machine, comprising a casing, a rotary element mounted in the casing, a circular series of balls supported in the rotary element, a hammer projecting into the casing, and a ball interposed between the inner end of the hammer and the balls in the rotary element, said last-mentioned ball adapted to be moved by the hammer into the path of movement of the first-mentioned balls, substantially as described.

7. A riveting machine, comprising a casing, a rotary element mounted in the casing, a circular series of balls supported in the rotary element, a hammer projecting into the casing, and a ball interposed between the inner end of the hammer and the balls in the rotary element, said last-mentioned ball adapted to be moved by the hammer into the path of movement of the first-mentioned balls, an arm pivoted at one end in the casing, and a socket in said arm supporting the ball, yet permitting rotary movement thereof, substantially as described.

8. A riveting machine, comprising a casing, a rotary element in the casing comprising two disks secured together, said disks having annular facing grooves and registering curved pockets, balls located in said pockets and projecting into the grooves, a pivoted arm in the casing, a ball supported by said arm, and a hammer projecting into the casing engaging the last-mentioned ball and adapted to move the ball into the path of movement of the balls carried by the rotary element, substantially as described.

9. A riveting machine comprising a hammer, a rotary element, a circular series of balls supported by said rotary element and constructed to impart movement to the hammer, a plate normally closing the lower end of the casing, a cylindrical barrel on said plate, a gear mounted to turn in said barrel

and with which said hammer is keyed, an idle gear supported on the plate and engaging the first-mentioned gear, and means for turning the idle gear, substantially as described.

10. A riveting machine, comprising a hammer, a rotary element, a circular series of balls supported in said rotary element, a device engaging the hammer and adapted to be moved by the hammer into the path of movement of the balls, a plate normally closing the lower end of the casing, a cylindrical barrel on said plate, a gear mounted to turn in said barrel and with which said hammer is keyed, an idler gear supported on the plate and engaging the first-mentioned gear, and means for turning the idle gear, substantially as described.

11. A riveting machine, comprising a casing, a rotary element mounted in the casing, a circular series of balls supported in the rotary element, a hammer projecting into the casing and adapted to be moved by the balls, a plate normally closing the lower end of the casing, a cylindrical barrel on said plate, a gear mounted to turn in said barrel and with which said hammer is keyed, an idle gear supported on the plate and engaging the first-mentioned gear, and means for turning the idle gear, substantially as described.

12. A riveting machine, comprising a casing, a rotary element mounted in the casing, a circular series of balls supported in the rotary element, a hammer projecting into the casing, and a ball interposed between the inner end of the hammer and the balls in the rotary element, said last-mentioned ball adapted to be moved by the hammer into the path of movement of the first-mentioned balls, an arm pivoted at one end in the casing, a socket in said arm supporting the ball, yet permitting rotary movement thereof, a plate normally closing the lower end of the casing, a cylindrical barrel on said plate, a gear mounted to turn in said barrel and with which said hammer is keyed, an idle gear supported on the plate and engaging the first-mentioned gear, and means for turning the idle gear, substantially as described.

13. A riveting machine comprising a hammer, a rotary element, a circular series of balls supported by said rotary element and constructed to impart movement to the hammer, a plate normally closing the lower end of the casing, a cylindrical barrel on said plate, a gear mounted to turn in said barrel and with which said hammer is keyed, an idle gear supported on the plate and engaging the first-mentioned gear, means for turning the idle gear, a nose screwed into the barrel, a clamping collar locked to the barrel and clamping the nose against movement, and a spring-pressed sleeve mounted on the plate.

- in the nose and projecting beyond the end thereof, substantially as described.
14. A riveting machine, comprising a hammer, means for reciprocating the hammer, an anvil below the hammer, a rivet supporting disk or table located between the hammer and the anvil, a worm wheel secured to turn with the disk or table and having teeth beveled at one side and straight on their other sides, whereby an alternate series of inclined and straight walled recesses are formed between the teeth, a segmental worm engaging the beveled faces of the teeth, and an annularly positioned key engaging the straight faces of the teeth, whereby an intermittent movement is imparted to the table, and said table locked while at rest, substantially as described.
15. A riveting machine, comprising a hammer, means for reciprocating the hammer, an anvil below the hammer, a rivet supporting disk or table located between the hammer and the anvil, a worm wheel secured to turn with the disk or table and having teeth beveled at one side and straight on their other sides, whereby an alternate series of inclined and straight walled recesses are formed between the teeth, a segmental worm engaging the beveled faces of the teeth, an annularly positioned key engaging the straight faces of the teeth, whereby an intermittent movement is imparted to the table, and said table locked while at rest, a sleeve with which said segmental cam and key are integral, a shaft to which said sleeve is fixed, and transmitting mechanism connecting the rotary element and the said last-mentioned shaft, substantially as described.
16. A riveting machine, comprising a hammer, means for reciprocating the hammer, an anvil below the hammer, a rivet supporting disk or table located between the hammer and the anvil, a worm wheel secured to turn with the disk or table and having teeth beveled at one side and straight on their other sides, whereby an alternate series of inclined and straight walled recesses are formed between the teeth, a segmental worm engaging the beveled faces of the teeth, an annularly positioned key engaging the straight faces of the teeth, whereby an intermittent movement is imparted to the table, and said table locked while at rest, a sleeve with which said segmental cam and key are integral, a shaft to which said

sleeve is fixed, and transmitting mechanism connecting the rotary element and the said last-mentioned shaft, cams on said last-mentioned shaft, and levers operated by the cams and adapted to move the anvil vertically while the table is still, substantially as described.

17. A riveting machine, comprising a casing, a rotary element in the casing, a vertically movable plunger projecting through the casing and constructed to be reciprocated by the rotary element, an anvil below the hammer, a rivet supporting disk or table located between the hammer and the anvil, a shaft, mechanism connecting the rotary element with the said shaft, whereby they are operated in unison, means between the shaft and the table, whereby an intermittent partial rotary movement is imparted to the table, cams on said shaft, levers fulcrumed between their ends, rollers on the ends of said levers in the path of movement of the cams, and the free ends of said lever constructed to elevate the anvil when moved by the cams, substantially as described.

18. A riveting machine, comprising a casing, a rotary element in the casing, a vertically movable plunger projecting through the casing and constructed to be reciprocated by the rotary element, an anvil below the hammer, a rivet supporting disk or table located between the hammer and the anvil, a shaft, mechanism connecting the rotary element with the said shaft, whereby they are operated in unison, means between the shaft and the table, whereby an intermittent partial rotary movement is imparted to the table, cams on said shaft, levers fulcrumed between their ends, rollers on the ends of said levers in the path of movement of the cams, a spindle supporting the anvil, a bracket clamped at one end around the spindle, threaded rods on said bracket, bars secured to said rods and projecting under the lower end of the spindle, and the free ends of said levers engaging said bracket, whereby the movement of the levers causes the movement of the spindle and the anvil, substantially as described.

In testimony whereof I have signed my name to this specification in the presence of two subscribing witnesses.
